UNITED STATES PATENT OFFICE.

HARRY A. DOUGLAS, OF BRONSON, MICHIGAN.

ELECTRIC SWITCHING MECHANISM.

Application filed November 17, 1927. Serial No. 233,870.

My invention relates to circuit controlling switching mechanism employing casings for the switch contacts and switch operating handles.

5 My invention has for its object the provision of improved means for assembling the switch casings with supports therefor.

In accordance with my invention, the switch casing terminates in a bearing sleeve 10 and has an enlargement thereon which is preferably in the form of a nut which is screwed upon the sleeve. A flange is also provided upon the sleeve, the support or mounting for the switch casing being connected 15 between the flange and nut, the nut being upon one side of the support, the contacts of the switching mechanism being upon the same side of the support with the nut. A hole is formed in the support which is 20 smaller than the flange but larger than the nut and the part of the switch casing to the rear of the nut to permit the nut and this part of the switch casing to be passed through the support. The flange, however, is larger 25 than the hole. In order that the nut may serve to clamp the flange against the support, I employ a washer, preferably U-shaped, which is inserted laterally of the casing sleeve between the nut and support. The aforesaid flange is desirably provided with 30 a skirt portion which is snugly received in the hole in the support whereby the casing is accurately positioned. The switch is operated by a shaft that has bearing in the sleeve 35 portion of the casing, this shaft being desirably movable longitudinally of the sleeve to constitute the switch a push and pull switch.

The invention will be more fully explained 40 by reference to the accompanying drawing in which Fig. 1 is a side elevation of the preferred embodiment of the invention with the switch support shown in section; Fig. 2 is a sectional view on line 2-2 of Fig. 1; 45 Fig. 3 is a sectional view on line 3-3 of Fig. 1; and Fig. 4 is a view partially in section and partially in elevation showing parts in separated relation and illustrating the manner in which they are clamped in assembly.

The switch casing illustrated is inclusive 50 of a body portion 1 and terminates in an exteriorly threaded bearing sleeve 2 of smaller diameter than said body portion. The parts 1 and 2 are desirably separately formed. As 55 shown, the body portion 1 is formed with a

circular opening at its front end, a portion 3 margining this opening being snugly received within an annular groove which is formed in the rear end of the sleeve. The body portion 1 of the casing is closed, at its rear end, by a disc of insulation 4 which is held in place by means of tongues 5 that are clinched over the disc. Two stationary contacts 6 and 7 are anchored upon said disc 60 within the casing body 1, these contacts being firmly united electrically and mechanically with the terminal blocks 8, 9 that are upon the exterior of the casing. Rivets 10, having shank portions passing through the disc, are desirably headed into assembly with said contacts and terminal blocks, as illustrated most clearly in Fig. 2. A third contact 11 is complementary to both of the contacts 6 and 7 and is movable into and out 65 of engagement with the latter contact while preferably being in permanent engagement with the other contact. In the embodiment of the invention illustrated, the contact 11 is in the form of a metallic collar which is 70 carried upon an insulating disc 12 which is secured upon the reduced inner end 13 of a handle shaft 14. In the embodiment of the invention shown, the shaft 14 is provided with a knob 15 and is movable thereby longitudinally of the bearing sleeve.

The support which I have illustrated for the switch casing, is in the form of a board or panel 16, such as a dash board of an automobile, the switch of my invention being of 90 particular utility in controlling certain automobile circuits. The casing is held in suitable assembly with the dash board by confining or clamping the dash board between the flange 17 upon the front end of the sleeve 95 and an enlargement 18 upon a portion of the sleeve to the rear of the dash board, this enlargement being desirably in the form of a nut which is employed to hold said flange in clamping engagement with the dash 100 board. Washers 19, 20 and 21 are interposed between the nut and the dash board. A circular hole 22 is formed through the dash board, this hole being sufficiently large to permit said nut, all the washers except washer 19, and the body portion 1 of the casing to be passed through the dash board from the front side thereof. The flange 17, however, is larger than said hole and engages and laps the same in the region of the hole. After 105 the parts 1, 18, 20 and 21 have been passed through the dash board, as illustrated in

110

Fig. 4, the washer 19, which is desirably U-shaped, is inserted laterally of the sleeve between the washer 20 and the dash board 16, this washer 19 being also larger or of greater diameter than the hole 22 so that when the nut 18 is tightened, the dash board 16 is firmly clamped between the flange 17 and the U-shaped washer 19. The washer 21 is desirably a spring washer so that the parts will not work loose after the clamping operation has been effected. In order that the switch structure may be aligned accurately with respect to the center of the hole 22, I form the flange 17 with a skirt portion 23 which is snugly received within the hole. The flange 17 is desirably assembled with the bearing sleeve 2 by having its central portion tightly received within an annular groove formed in the outer end of the sleeve.

20 Changes may be made without departing from the invention.

Having thus described my invention, I claim:

1. The combination with a casing terminating in an exteriorly threaded bearing sleeve; of an electric switch having complementary contacts within the casing; a shaft within said sleeve and in actuating relation to one of said contacts and accessible for operation at the outer end of the sleeve; a flange upon the sleeve; a nut screwed upon the threads of the sleeve; a support having a hole therethrough through which the nut and the portion of the casing where said contacts are disposed are passed to one side of said support, said flange being upon the other side of the support and lapping the same in the region of the hole therethrough, and having a skirt portion snugly received in said hole to position the casing with respect to the support; and a washer formed for insertion, and inserted, laterally of the sleeve and clamped by the nut between the nut and support.

45. 2. The combination with a casing terminating in an exteriorly threaded bearing sleeve; of an electric switch having complementary contacts within the casing; a shaft within said sleeve and in actuating relation to one of said contacts and accessible for operation at the outer end of the sleeve; a flange upon the sleeve; a nut screwed upon the threads of the sleeve; a support having a hole therethrough through which the nut and the portion of the casing where said contacts are disposed are passed to one side of said support, said flange being upon the other side of the support and lapping the same in the region of the hole therethrough; and a washer formed for insertion, and inserted, laterally of the sleeve and clamped by the nut between the nut and support.

60. 3. The combination with a casing terminating in a bearing sleeve and having an enlargement thereon; of an electric switch hav-

ing complementary contacts within the casing; a shaft within said sleeve and in actuating relation to one of said contacts and accessible for operation at the outer end of the sleeve; a flange upon the sleeve; a support having a hole therethrough through which the enlargement on the casing and the portion of the casing where said contacts are disposed are passed to one side of said support, said flange being upon the other side of the support and lapping the same in the region of the hole therethrough, and having a skirt portion snugly received in said hole to position the casing with respect to the support; and a washer formed for insertion, and inserted, laterally of the sleeve and confined between said enlargement and support.

4. The combination with a casing terminating in a bearing sleeve and having an enlargement thereon; of an electric switch having complementary contacts within the casing; a shaft within said sleeve and in actuating relation to one of said contacts and accessible for operation at the outer end of the sleeve; a flange upon the sleeve; a support having a hole therethrough through which the enlargement on the casing and the portion of the casing where said contacts are disposed are passed to one side of said support, said flange being upon the other side of the support and lapping the same in the region of the hole therethrough; and a washer formed for insertion, and inserted, laterally of the sleeve and confined between said enlargement and support.

5. The combination with a casing terminating in an exteriorly threaded bearing sleeve; of an electric switch having complementary contacts within the casing; a shaft within said sleeve and in actuating relation to one of said contacts and accessible for operation at the outer end of the sleeve; a flange upon the sleeve; a nut screwed upon the threads of the sleeve; a support having a hole therethrough through which the nut and the portion of the casing where said contacts are disposed are passed to one side of said support, said flange being upon the other side of the support and lapping the same in the region of the hole therethrough, and having a skirt portion snugly received in said hole to position the casing with respect to the support; and a U-shaped washer inserted laterally of the sleeve and clamped by the nut between the nut and support.

6. The combination with a casing terminating in an exteriorly threaded bearing sleeve; of an electric switch having complementary contacts within the casing; a shaft within said sleeve and in actuating relation to one of said contacts and accessible for operation at the outer end of the sleeve; a flange upon the sleeve; a nut screwed upon the threads of the sleeve; a support having a hole therethrough through which the nut

and the portion of the casing where said contacts are disposed are passed to one side of said support, said flange being upon the other side of the support and lapping the same in 5 the region of the hole therethrough; and a U-shaped washer inserted laterally of the sleeve and clamped by the nut between the nut and support.

7. The combination with a casing terminating in a bearing sleeve and having an enlargement thereon; of an electric switch having complementary contacts within the casing; a shaft within said sleeve and in actuating relation to one of said contacts 10 and accessible for operation at the outer end of the sleeve; a flange upon the sleeve; a support having a hole therethrough through which the enlargement on the casing and the portion of the casing where said contacts 15 are disposed are passed to one side of said support, said flange being upon the other side of the support and lapping the same in the region of the hole therethrough, and having a skirt portion snugly received in 20 said hole to position the casing with respect to the support; and a U-shaped washer inserted laterally of the sleeve and confined between said enlargement and support.

8. The combination with a casing terminating in a bearing sleeve and having an enlargement thereon; of an electric switch having complementary contacts within the casing; a shaft within said sleeve and in actuating relation to one of said contacts 25 and accessible for operation at the outer end of the sleeve; a flange upon the sleeve; a support having a hole therethrough through

which the enlargement on the casing and the portion of the casing where said contacts are disposed are passed to one side of said support, said flange being upon the other side of the support and lapping the same in the region of the hole therethrough; and a U-shaped washer inserted laterally of the sleeve and confined between said enlargement and support. 40 45

9. The structure of claim 1 wherein the shaft is slidable longitudinally of the bearing sleeve.

10. The structure of claim 2 wherein the shaft is slidable longitudinally of the bearing sleeve. 50

11. The structure of claim 3 wherein the shaft is slidable longitudinally of the bearing sleeve. 55

12. The structure of claim 4 wherein the shaft is slidable longitudinally of the bearing sleeve.

13. The structure of claim 5 wherein the shaft is slidable longitudinally of the bearing sleeve. 60

14. The structure of claim 6 wherein the shaft is slidable longitudinally of the bearing sleeve.

15. The structure of claim 7 wherein the shaft is slidable longitudinally of the bearing sleeve. 65

16. The structure of claim 8 wherein the shaft is slidable longitudinally of the bearing sleeve. 70

In witness whereof, I hereunto subscribe my name.

HARRY A. DOUGLAS.
